Primary Examiner—Lucy Lieberman
Attorney, Agent, or Firm—Lawrence D. Schuler; Michele G. Mangini[57] **CLAIM**

The ornamental design for a bottle, as shown and described.

DESCRIPTION

FIG. 1 is a front perspective view of a bottle showing our new design;

FIG. 2 is a rear perspective view thereof;

FIG. 3 is a front elevational view thereof;

FIG. 4 is a rear elevational view thereof;

FIG. 5 is a right side elevational view thereof, the left side elevational view being a mirror image;

FIG. 6 is a top plan view thereof; and,

FIG. 7 is a bottom plan view thereof.

The broken line showing of the cap in FIGS. 1-6 is for illustrative purposes only and forms no part of the claimed design.
